P. S. LIETZ,
BED FOR GAME TABLES AND METHOD OF MAKING SAME.
APPLICATION FILED SEPT. 4, 1917.

1,328,332.

Patented Jan. 20, 1920.

UNITED STATES PATENT OFFICE.

PAUL S. LIETZ, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

BED FOR GAME-TABLES AND METHOD OF MAKING SAME.

1,328,332.

Specification of Letters Patent. Patented Jan. 20, 1920.

Application filed September 4, 1917. Serial No. 189,660.

To all whom it may concern:

Be it known that I, PAUL S. LIETZ, a citizen of the United States, residing at Chicago, in the county of Cook and State of Illinois, have invented certain new and useful Improvements in Beds for Game-Tables and Methods of Making Same, of which the following is a specification.

My invention relates to game tables and has for its primary object the provision of a satisfactory substitute for slate beds now commonly used on billiard, pocket billiard and other game tables.

Further objects and advantages of my invention will be apparent as it is better understood by reference to the following specification when read in connection with the accompanying drawing illustrating the preferred embodiment thereof, in which—

20 The figure is a sectional view of a portion of a table bed constructed in accordance with my invention.

My invention comprises a bed embodying a core preferably of wood which is wholly inclosed within a shell, applied thereto in a plastic condition, which when cooled and subjected to pressure becomes dense, moisture proof and very hard, making an ideal bed for game tables.

30 In carrying out my invention I first prepare a plastic composition consisting of the following ingredients in the proportions noted.

35 Earthy material and cement----- 12 parts
Asbestos ----- 2 parts
Rosin ----- 12 parts
Common soap----- 2 parts

The earthy material may be clay, sand, 40 ground slate, cement, plaster of Paris or the like. This material with the asbestos is first ground to a powder sufficiently fine to pass a 60 mesh sieve. The object of the earthy mixture consisting of cement, asbestos, shale, plaster of Paris or limestone is to thoroughly fill the voids of the coarse material—namely, sand, clay or slate. The proportions of the finer to the coarser material is preferably half and half. All 50 coarse material is removed. The ground material must be free from moisture and may be dried if necessary. It is heated to a temperature of 250° F. and is then mixed in any suitable mixing apparatus with the binder consisting of rosin and common soap,

which is previously melted and heated to a temperature of 250° F. The composition will have about the consistency of molasses and is ready to be cast.

The core is constructed of seasoned wood 60 strips 5 preferably about seven-eighths of an inch in thickness and is slightly smaller than the dimensions of the bed of the table for which it is intended. The strips should be tongued and grooved and glued together 65 with a heat withstanding glue and both sides of the strips should be roughened so that the plastic material 6 will readily adhere thereto.

The core is centered in a frame leaving a 70 space of about three-eighths of an inch between the side faces of the core and the frame. The plastic material is then run into the frame on both sides of the core and around its edges until the core is completely 75 inclosed, after which it is subjected to a pressure of about fifty tons per square foot until the plastic material is about one-eighth of an inch thick on each face of the core. The bed is then cooled, removed from 80 the press and placed in a seasoning press where it remains for at least thirty days before being used.

The frames are constructed of cast iron and are carefully machined so that the interior dimensions are exactly the same as the desired dimensions of the table bed. They are provided with steam heating pipes through which live steam may be injected to bring the interior of the frame and the 90 core to a uniform temperature of 250° F. before the plastic material is introduced. The steam is cut off before the pressing operation commences and cold water is subsequently forced through the pipes to cool the 95 finished bed.

Beds constructed of the material and in the manner hereinbefore specified are found to fill a long felt need in the art for a satisfactory bed which is cheaper than slate yet 100 has all of its desirable qualities. The wood core is so thoroughly protected by the moisture proof coating that it cannot warp or expand or contract under changing atmospheric and temperature conditions. When 105 mounted on the table it remains perfectly true and level, indefinitely.

Various changes may be made in the form, construction and arrangement of the parts without departing from the spirit and scope 110

of the invention or sacrificing any of its material advantages, the forms hereinbefore described being merely the preferred embodiment thereof.

5 I claim:

1. A bed for game tables comprising a core substantially co-extensive in area with the area of the bed, and a shell completely inclosing said core and consisting of a hard, dense moisture proof composition.
2. A bed for game tables comprising a core substantially co-extensive in area with the area of the bed, and a shell completely inclosing said core and consisting of a hard, dense moisture proof composition of earthy material, and a binder therefor.
3. A bed for game tables comprising a wood core substantially co-extensive in area with the area of the bed, and a shell completely inclosing said core and forming a hard, dense moisture-proof envelop therefor.
4. A bed for game tables comprising a wood core substantially co-extensive in area with the area of said bed, and a shell completely inclosing said core and consisting of earthy material, and a binder therefor, said shell forming a hard, dense moisture proof envelop for said core.
5. A bed for game tables comprising a wood core substantially co-extensive in area with the area of said bed, and a dense, hard moisture proof shell completely inclosing said core and having a smooth level upper surface.
- 35 6. A bed for game tables comprising a wood core substantially co-extensive in area

with the area of said bed, and a dense, hard moisture proof shell applied to said core in a plastic condition and having a smooth level upper surface.

7. A bed for game tables comprising a wood core substantially co-extensive in area with the area of the bed, and a dense, hard moisture proof shell, inclosing said core and consisting of earthy material, and a binder therefor, said shell having a smooth level upper surface.

8. A bed for game tables comprising a core of abutting wood strips adhesively secured together, said core being substantially co-extensive in area with the area of said bed, and a dense, hard, moisture proof shell inclosing said core.

9. A bed for game tables comprising a core of abutting wood strips adhesively secured together, said core being substantially co-extensive in area with the area of the bed, and a facing thereon consisting of earthy material and a plastic binder therefor, the surface of said facing being smooth and level.

10. A bed for game tables consisting of a core of abutting wood strips adhesively secured together, said core being substantially co-extensive in area with the area of the bed, and a dense, hard moisture proof facing on said core and consisting of earthy material and a rosin binder therefor.

PAUL S. LIETZ.
